ARTICLE SUPPORTING DEVICE

Byron F. Bower, Batavia, Ill., assignor to Western Electric Company, Incorporated, New York, N. Y., a corporation of New York

Application October 27, 1933, Serial No. 695,419

3 Claims. (Cl. 204—5)

This invention relates to article supporting devices, and more particularly to devices for supporting articles to be treated.

In the treating of articles in a plating bath, it is the common practice to employ racks for suspending the articles in the bath, the articles being fastened to and suspended from a cross bar of the rack by means of tie wires inserted through individual apertures in the cross bar. After each plating operation the tie wires are removed individually from the bar by untwisting and/or cutting them with pliers, and thereafter pulling them through the apertures in the bar, which operation is costly, tedious, and results in blisters 10 on the operator's fingers.

The object of this invention is to provide a simple and practical device for supporting articles to be treated and which upon completion of the treating operation may be conveniently and rapidly unloaded of the tie wires.

In accordance with one embodiment of this invention as applied to an article supporting rack for a plating bath there is provided a rack comprising a cross bar having spaced apertured depending lugs and a retractable pin which is inserted through the apertures of the lugs, the tie wires supporting the articles to be treated being looped around the pin between the spaced lugs. Upon completion of the plating operation and the removal of the rack from the bath all of the tie wires with or without the articles attached thereto may be expeditiously detached and dropped from the rack by simply pulling out the pin.

Other features and advantages of the invention will become apparent from the following detailed description when used in conjunction with the accompanying drawing, in which

Fig. 1 is a side view of one form of an article supporting device embodying the features of this invention, and

Fig. 2 is an end view thereof.

Referring now to the drawing in detail, the plating rack illustrated comprises two identical vertical side members 10, formed of copper or other conducting metal through which the current is adapted to be conducted to the plating bath (not shown). The upper ends of the member 10 are each provided with a hook portion 11 for engagement with a cathode conductor bar 12. Interconnecting the member 10 is a handle 13 having downwardly extending ends riveted to the members 10 adjacent their lower ends. Brazed to or otherwise secured to the lower ends of the members 10 below the handle 13 is a metal cross bar 15 having opposite ends thereof pro-

jecting from the associated members for an appreciable distance. A series of spaced depending ears or lugs 16 are formed upon the cross bar 15 along its lower portion and below the lower ends of the members 10. The lugs 16, which extend from one end to the other of the cross bar 15, are provided with circular alined apertures 17 for the reception of a retractable metal rod or pin 18 which is inserted through the alined apertures, one end of the pin being formed with a right angle 19 serving as a hand grip for inserting and withdrawing the pin from the cross bar 15.

In the use of the above described plating rack articles 20 to be plated are suspended from the pin 18 by metal tie wires 21 which have their upper ends looped around the portions of the pin between the spaced lugs 16 of the cross bar 15 and then twisted around the wires, and the lower ends of the wires are inserted through apertures in the article or otherwise engaged therewith and 20 then twisted around the wire. As an alternative, the upper loop on the tie wires may be made before being attached to the rack and the tie wires may be successively mounted on the pin 18 while the latter is being inserted in the lugs 16. 25 Thereafter the rack is supported on the cathode conductor bar 12 above the plating bath by means of the hook portions 11 of the side members 10, the articles being immersed in the plating bath. The current is switched on and the current flows 30 through the bar 12, the members 10, the cross bar 15, the pin 18, and the individual article supporting wires 21 and to the articles 20 which are electroplated in the well known manner. Upon completion of the plating of the articles 20 the 35 current is switched off and the rack is removed from the cathode conductor bar 12 and suspended from a convenient point by means of the handle 13. Preferably the articles 20 are first removed from the wires 21, still attached at their 40 upper ends to the rack by the pin 18, by slightly untwisting the lower wire ends and then pulling the articles from the wires. The wires 21 may then be expeditiously and simultaneously detached or unloaded from the rack by simply 45 pulling the pin 18, by means of the hand grip 19, out from the lugs 16 of the cross bar 15, the tie wires 21, which it is not the practice to use a second time, dropping into a refuse receptacle.

In case it is desired to reload the rack with 50 articles 20 to continue the plating operation with a minimum of delay it will be obvious that instead of first removing the plated articles from the tie wires 21 and then dropping the wires from the pin 18, as described above, the tie wires with 55

the attached articles may be removed together from the rack by first pulling the pin 18 out from the lugs 16 of the cross bar 15 and subsequently detaching the articles from the wires.

It will be evident that with a rack of the type described there is no necessity of individually untwisting and/or cutting the tie wires 21 and thereafter pulling thereon to remove them from the rack, which is necessary in the common type 10 of plating racks in which the tie wires are threaded through individual apertures in the cross bar, which operation is uneconomical, tedious, and harmful to the operator's fingers.

Although there is herein shown and described 15 a specific embodiment of this invention, it should be understood that modifications may be made without departing from the spirit and scope of the appended claims.

What is claimed is:

20 1. An electroplating rack for supporting articles to be electroplated comprising a pair of spaced supporting members, a cross member connecting said supporting members, said cross member having a plurality of spaced portions 25 provided with aligned apertures, and a retractable

rod inserted through the apertures upon which articles may be freely suspended between the spaced portions of said cross member and upon retraction of said rod permitting the suspended articles to drop from the device. 5

2. An electroplating rack comprising a pair of spaced conducting and supporting members, a conducting cross bar connecting said members, said bar being formed with a plurality of spaced depending aligned apertured lugs, and a retractable conducting rod inserted through the apertures upon which articles may be freely suspended between the spaced lugs of said cross bar and upon retraction of said rod permitting the suspended articles to be expeditiously released from 15 the rack.

3. An electroplating rack comprising a supporting and conducting member, a cross bar conductively connected to said member, a plurality of spaced and downwardly extending apertured 20 lugs on said cross bar, and a rod withdrawable from said lugs and extending through said apertures for receiving looping articles supports between said lugs.
